(57) **CLAIM**

The ornamental design for a differential signal terminal with an opening, as shown and described.

DESCRIPTION

FIG. 1 is a front, top, and right side perspective view of a differential signal terminal with an opening, which shows my new design;

FIG. 2 is a front view thereof;

FIG. 3 is a back view thereof;

FIG. 4 is a left side view thereof;

FIG. 5 is a right side view thereof;

FIG. 6 is a top plan view thereof; and,

FIG. 7 is a bottom plan view thereof.

1 Claim, 5 Drawing Sheets
